(57) **CLAIM**

The ornamental design for a watercraft vessel with forward bottom window for underwater viewing, as shown and described.

DESCRIPTION

FIG. 1 is a top perspective view of my new design for a watercraft vessel with forward bottom window for underwater viewing;

FIG. 2 is a bottom perspective view thereof;

FIG. 3 is a top view thereof;

FIG. 4 is a bottom view thereof;

FIG. 5 is a right side view thereof, a left side view (omitted) being a mirror image thereof;

FIG. 6 is a front view thereof; and,

FIG. 7 is a rear view thereof.

1 Claim, 6 Drawing Sheets
